RISING SUPPORT

Filed March 19, 1941

FIG. 1

Inventor
Hugh Starks

By *Watson E. Coleman*
Attorney

UNITED STATES PATENT OFFICE

2,310,043

RISING SUPPORT

Hugh Starks, Grand Junction, Colo., assignor of one-fifth to Silmon L. Smith and one-fifth to Charles M. Holmes, both of Grand Junction, Colo.

Application March 19, 1941, Serial No. 384,183

4 Claims. (Cl. 206—41.1)

This invention relates to an automatic rising support for use in connection with a tobacco can, and it is an object of the invention to provide a device of this kind which may be readily placed within the can below the tobacco container or package in a folded condition and which device, as the container or package is raised within the can, will unfold in a manner to hold the container or package in its raised position.

It is also an object of the invention to provide a device of this kind comprising a member provided with holding legs or props which, when the device is initially applied, are in folded or collapsed position, together with retractile means for extending the legs or props into effective position when the container or package within the can is raised, the extended legs or props co-acting with the can in a manner to maintain the container or package in its raised position with respect to the can.

In order that my invention may be the better understood, I will now proceed to describe the same with reference to the accompanying drawing, wherein

Figure 1 is a view, partly in side elevation and partly in section, illustrating a support constructed in accordance with an embodiment of my invention and in extended or supporting position, the container or package being partly lifted out of the can;

Figure 2 is an enlarged fragmentary detailed sectional view showing the support in a collapsed condition and in its initial placement within the can;

Figure 3 is a view in bottom plan of the device folded or collapsed;

Figure 4 is a fragmentary view, partly in section and partly in elevation, illustrating a support constructed in accordance with another embodiment of the invention; and

Figure 5 is a fragmentary sectional view taken substantially on the line 5—5 of Figure 4.

As disclosed in the accompanying drawing the improved attachment comprises an elongated flat body member 1 of cardboard or other preferred material. This member 1 is of such dimensions as to be snugly fitted within a tobacco can C between the container or package P within the can C and the bottom 2 of the can. This member 1 may have printed or otherwise produced thereon advertising or other matter as may be desired by the distributor. Each end portion of the member 1 is provided with a short returned tab 3 in close contact with the adjacent end portion of the member 1 and maintained in such

position by a surrounding adhesive strip 4, or otherwise as may be preferred.

The tabs 3 have their inner ends continued by the elongated flat legs or props 5 each of which readily swings on the score line 6 separating the leg or prop from its tab 3. The free end portions of the legs or props 5 are provided with the slits 7 in which are engaged the end portions of a retractile member 8 herein disclosed as an elastic band. The intermediate portion of this member 8 is extended lengthwise across the upper or outer face of the member 1 whereby the member 8 is placed under such tension as to automatically swing the legs or props 5 downwardly and outwardly to lift the member 1 as the container or package P is raised within the can. These legs or props 5 as they swing outwardly slide one upon the other and one upon the bottom 2 of the can C and when the lower or outer end portions of the legs or props 5 come into contact with the edge walls 9 of the can C said legs or props 5 have each passed outwardly beyond a vertical center and thus provide effective means for preventing depression of the member 1 within the can C with a resultant lowering of the container or package P.

Initially the legs or props 5 are in close overlying relation and in compact position with respect to the member 1. When the container or package P is placed within the can C the attachment is disposed over the bottom of the container or package and held in such position by a looped string or the like having its strands 35 of a length to extend out beyond the open end of the can C after the container or package P has been fully inserted within the can C. After this operation the string or the like can be readily drawn out, leaving the attachment in its desired folded or compact position within the can C between the bottom 2 of such can and the container or package P.

It is stated at this time that the means employed to allow for the proper placement of the attachment within the can forms no part of the present invention and it is, therefore, to be understood that any means may be employed to facilitate the proper effective placing of the attachment.

In the embodiment of the invention as illustrated in Figures 4 and 5 the underlying tabs 10 at the end portions of the elongated member 11 are maintained in desired position by the staples 12. Extending longitudinally over the upper or outer face of the member 11 at the trans-

verse center thereof and underlying the staples 12 is a light wire strand 14 which extends beyond the opposite ends of the member 11. Suitably anchored or secured to these extended end portions of the strand 14 are the retractile members 15 herein disclosed as coil springs. These members are also secured, as at 16, to the upper end portions of the wire strands 17 which extend along the lower outer faces of the legs or props 18 and are suitably anchored, as at 19, to said legs or props 18.

With the use of either of the embodiments of the invention is herein disclosed it is believed to be obvious that when the smoker pulls up the tobacco package or container within the can to facilitate having access to the tobacco in the lower portion of the container or package, as is a well-known custom, the legs 5 or 18 will automatically swing outward and thereby raise the member 1 or the member 11, whereby either of such members will effectively support the raised container or package of tobacco.

From the foregoing description it is thought to be obvious that a device constructed in accordance with my invention is particularly well adapted for use by reason of the convenience and facility with which it may be assembled and operated.

I claim:

1. As a new article of manufacture, a support for a package when lifted within a can comprising an elongated member for placement within the can between the bottom wall thereof and the applied package, returned tabs at the opposite end portions of the member and in close contact therewith from below and extending a material distance inwardly from the ends of the elongated member, means for maintaining the tabs in such positions, props in swinging connection with the inner extremities of the tabs, said props being closely folded one with respect to the other and with respect to the member when the device is initially applied within the can between the bottom of the can and the package therein, and means for swinging the props away from the member and away from each other to raise the member when the package within the can is lifted.

2. As a new article of manufacture, a support for a package when lifted within a can comprising

an elongated member for placement within the can between the bottom wall thereof and the applied package, returned tabs at the opposite end portions of the member and in close contact therewith from below and extending a material distance inwardly from the ends of the elongated member, means for maintaining the tabs in such positions, props in swinging connection with the inner extremities of the tabs, said props being closely folded one with respect to the other and with respect to the member when the device is initially applied within the can between the bottom of the can and the package therein, and means for swinging the props away from the member and away from each other to raise the member when the package within the can is lifted, the member, tabs and props comprising a single length of material.

3. As a new article of manufacture, a device for supporting a package when raised within a can comprising a member to be placed between the bottom of the can and the package therein, swinging props carried by the opposite end portions of the member, said props being folded to lie one closely adjacent to the other and adjacent to the member when the device is applied within the can, and a retractile member disposed lengthwise over the upper face of the member and extending over the outer faces of the props and secured to the outer end portions of the props for swinging said props into extended position to raise the member when the package within the can is lifted.

4. As a new article of manufacture, a device for supporting a package when raised within a can comprising a member to be placed between the bottom of the can and the package therein, swinging props carried by the opposite end portions of the member, said props being folded to lie one closely adjacent to the other and adjacent to the member when the device is applied within the can, a member extending lengthwise of the first-named member and overlying the outer face thereof, and retractile members secured to the extremities of the second member and to the outer end portions of the props for swinging said props into extended position to raise the member when the package within the can is lifted.

HUGH STARKS.
